UNITED STATES PATENT OFFICE.

WILLIAM J. WALKER, OF ST. LOUIS, AND ALEXANDER L. BEDEFORD, OF SAVANNAH, MISSOURI.

VEHICLE-WRENCH.

SPECIFICATION forming part of Letters Patent No. 499,863, dated June 20, 1893.

Application filed January 23, 1893. Serial No. 459,413. (No model.)

To all whom it may concern:

Be it known that we, WILLIAM J. WALKER, of St. Louis, and ALEXANDER L. BEDEFORD, of Savannah, Missouri, have invented certain new and useful Improvements in Vehicle-Wrenches, of which the following is a full, clear, and exact description, reference being had to the accompanying drawings, forming a part hereof.

Our invention has relation to improvements in vehicle wrenches and consists in the novel arrangement and combination of parts more particularly described in the specification and set out in the claims.

In the drawings Figure 1 is a perspective view of our complete invention. Fig. 2 is a plan view of the socket showing in dotted lines the various sizes of nuts located therein; and Fig. 3 is a vertical cross section of the socket.

In carrying out our invention the socket referred to is provided with four lugs superposed thereon, the lugs being separated by spaces at the angles or corners of the socket. These spaces allow for the reception of a maximum sized nut, at the same time reducing to a minimum the quantity of material composing the wrench. Ordinarily, in cases where the band on the hub of a carriage comes in close proximity to the nut secured to the axle, and which nut said band embraces, the rigid wrench as now used cannot be inserted within the band to grasp the nut. Especially is this true in cases where the nuts are small as in light buggies. In compact structures of this sort our improved wrench is particularly applicable, as by our construction we reduce the circumferential size of the wrench by dispensing with the metal which ordinarily enters into the corners of such wrenches. The spaces at the corners of the socket allow the corners of the maximum size nuts to pass, and thus with a wrench composed of the minimum quantity of material the maximum number of nuts can be operated one wrench doing the work of two ordinary wrenches under old constructions.

Referring to the drawings, 1 represents the handle of the wrench one end of which is provided with three different sized rigid jaws 2 for receiving nuts of various sizes, and formed

with said handle and adjacent to said jaws is a hammer 3 to be employed in cases of necessity.

4 represents the socket of the wrench the outer surface of which may be of any suitable shape but preferably of the construction shown in Fig. 1. The socket is composed of four lugs located or superposed upon the main portion 5 thereof.

6 represents the lugs referred to which are separated at the corners of the socket by spaces 7 which allow the corners of the largest sized nuts to pass as shown in dotted lines Fig. 2. The main portion 5 of the socket has formed on its inner walls four right angular grooves 8 midway between the four corners 9, which grooves are adapted to receive the four corners of the smallest nut 10 as shown in dotted lines Fig. 2. The four corners and the walls 11 at right angles thereto are adapted to receive the next larger nut 11 as shown in dotted lines in Fig. 2. Formed on the inner walls or surfaces of each lug 6 are right angular grooves 12 which receive the corners of the next larger nut 13 also shown in dotted lines in Fig. 2. Said lugs are provided with plane surfaces 14 which are eight in number and which come in contact with the sides of the nut 15 shown in dotted lines Fig. 2. A socket constructed as above described is applied to nuts of various sizes from one side of the socket only, and when thus applied hexagonal as well as square nuts can be accommodated.

Of course it will be understood that hexagonal nuts will not be accommodated snugly within the socket, but as the same is constructed to receive nuts of various sizes the socket will grasp the nuts sufficiently for turning the same.

In constructing the socket a continuous shoulder 16 is formed having on each of the four sides thereof two surfaces 17 which incline toward each other, and into the right angular shaped grooves 8, as shown in Figs. 1 and 3. These inclinations allow the nut 13 to enter farther into the right angular shaped grooves 12 of the lugs 6 and thus enable said lugs to take better hold of the nut. Another object of the inclined surfaces is to transfer a portion of the strain taken by the lugs to the body portion of the socket.

From the foregoing description the operation of the wrench is obvious.

Having described our invention, what we claim is—

1. A rigid vehicle wrench comprising a main portion 5, right angular grooves 8 formed on the inner walls of the same between the four corners thereof, a continuous shoulder 16 formed by said main portion and surfaces 17 inclined toward each other and into the right angular shaped grooves 8, substantially as set forth.

2. A wrench comprising a socket having a main portion 5, right angular grooves 8 formed

on the inner walls of the same, between the 15 corners 9, lugs 6 superposed on said portion 5 providing spaces 7, right angular grooves 12 formed on the said lugs, plane surfaces 14 also formed on said lugs, a continuous shoulder 16 having inclined surfaces 17, and a handle for 20 said socket, substantially as set forth.

In testimony whereof we affix our signatures in the presence of two witnesses.

WILLIAM J. WALKER.

ALEXANDER L. BEDFORD.
